Inventor
Harry A. Douglas.
By L. A. Craig & Atty.

UNITED STATES PATENT OFFICE.

HARRY A. DOUGLAS, OF BRONSON, MICHIGAN.

LOCK.

Application filed January 17, 1927. Serial No. 161,598.

My invention relates to locks and has for one of its objects the provision of a bolt or tumbler or tumblers included in the construction thereof and movable into one adjustment to have locking engagement with a guard and into an alternative adjustment out of such engagement and operable by a key into one adjustment and self operating into the alternative adjustment, upon the withdrawal of the key, or self holding if placed in alternative adjustment by the key.

In carrying out this object of my invention, each tumbler or bolt carries a spring which is placed under tension when the tumbler is operated by the key into one adjustment or position and which spring serves to place or hold the tumbler in its alternative adjustment or position upon the withdrawal of the key.

The tumblers are preferably formed of strip metal and the springs carried thereby are in the nature of tongues that are desirably integrally formed with the tumblers. There is a key receiving member, in the nature of a tumbler barrel or carrier, upon which the spring is pressed when the tumblers are moved by the key, the tongues thereby being placed under tension. When the key is removed, these spring tongues yield their tension and, in so doing, place or hold the tumblers in their alternative adjustments. The key receiving member is desirably also movable by the key, preferably rotatively, and the guard is desirably in the form of a shell which receives the key receiving member. This shell has a slot in its side, if there be but one tumbler or bolt, and slots in opposite sides thereof, if there is more than one tumbler, the key receiving member adjusting the tumbler or tumblers into and out of register with the slot or slots.

In accordance with another feature of the invention, the tumbler barrel or key receiving member and the tumblers carried thereby have interengaging holding portions that cooperate to hold the tumblers inoperative when moved beyond their normal range. The holding portions upon the tumblers are desirably the aforesaid springs and the holding portions upon the tumbler barrel are desirably of recessed formation which receive the ends of the springs when the tumblers are excessively moved as by a thief who is endeavoring to defeat the lock.

The invention has other characteristics and will be more fully explained in connection

with the accompanying drawings in which Fig. 1 is a side view of one form of lock with parts broken away and shown in section and a mounting board or plate upon which the lock is secured; Fig. 2 is a front view, on a smaller scale; Fig. 3 is a rear view on a smaller scale; Fig. 4 is another side view taken at right angles to the direction at which Fig. 1 is taken; Fig. 5 is a perspective view of the tumbler barrel with parts broken away; Fig. 6 is a sectional view on line 6—6 of Fig. 5; Figs. 7 and 8 are side elevations of two adjacent tumblers having symmetrically related spring tongues; Fig. 9 is a sectional view on line 9—9 of Fig. 1, the key being omitted in Figs. 1 to 9 inclusive and in Fig. 10 which is a sectional view on line 10—10 of Fig. 9; Fig. 11 is a view similar to Fig. 9 with the key in place and tumblers in positions to which they are shifted by the key; Fig. 12 is a sectional view on line 12—12 of Fig. 11; Fig. 13 is a sectional view on line 13—13 of Fig. 12; and Fig. 14 is a perspective view of a portion of the mounting and the shell which is to be fixedly assembled with the mounting and in which the tumbler barrel may be turned.

The mounting plate 1 may be the end wall of a casing enclosing a switch which may be controlled by the lock, such as the ignition switch of an automobile or other automotive vehicle. Obviously, however, the lock may be otherwise disposed. The guard 2 is carried by the mounting plate 1. In the form of the invention illustrated, this guard is in the form of a metallic sleeve or shell having tumbler receiving slots 3 and 4 on diametrically opposite sides thereof. Ears 5 are struck from the shell between the ends of the shell and near the front end, these ears being bent into the notches 6 that are formed in the collar 7 that is pressed rearwardly from the plate 1. The front end of the shell is formed with a flange 8 which is spaced apart from the front face of the mounting plate 1, the rear annular shoulder 9 of a collar 10 being snugly received between said flange and plate. The collar 10 has a front annular shoulder 11 which extends inwardly beyond the bore of the shell or locking guard 2, which is held in fixed relation with the plate 1 by the structural features described. The key receiving member, the tumbler barrel 12, is located within the shell or guard 2 and as this tumbler barrel is desirably rotatable, it is made cylindrical to turn within

the shell bore that is also cylindrical and of the same diameter where the tumbler barrel is rotatably supported by the shell. The front annular shoulder 11 of the collar 10 engages 5 the annular shoulder 12' on the front end of the tumbler barrel to prevent axial movement of the tumbler barrel in the forward direction. The ears 2' upon the rear end of the shell 2 engage the rear end of the tumbler barrel to prevent rearward movement 10 of the tumbler barrel. Where the tumbler barrel is adapted to be moved by the key, it is usually employed to transmit motion to some device extraneous to the lock, such a 15 device being, for example, a switch which controls the ignition circuit of an automotive vehicle.

In the drawings I have illustrated a ring 13 having a flattened bore with which the 20 flattened inner end 14 of the tumbler barrel has fixed engagement. This ring 13 may be employed in any suitable way. I have illustrated a pin 15 thereon which may be employed to transmit motion to some device 25 that is to be operated by the tumbler barrel. Obviously, other means may be employed for enabling the tumbler barrel to transmit motion. The key 16 is shown of flat form with a groove 17 in one side thereof, this key being 30 receivable within the oblong bore 18 formed in the tumbler barrel, said groove 17 in the key receiving the ribs 19 formed upon the tumbler barrel and projecting into the bore 18, said ribs serving to guide the key 35 in its movement into the tumbler barrel and placing the wards upon the key in proper position with respect to the tumblers or bolts that are arranged in two sets, 20 and 21. These tumblers are in the form of oblong 40 plates which are receivable in the grooves 22 that extend transversely of the tumbler barrel bore 18. The tumblers are formed with oblong openings 23 extending lengthwise thereof and through which the key is 45 passed, the openings 23 being variously located lengthwise of the different tumblers to cooperate with the wards upon the key so that when the key is fully inserted, the tumblers will be withdrawn from the slots 3 and 50 4 and entirely into the bore of the shell 2, Figs. 11 and 12. When the tumblers are thus withdrawn entirely within the bore of the shell 2, the key may be turned to turn the tumbler barrel and the motion transmitting ring 13 fixed upon the tumbler barrel. When the key is turned following the withdrawal of the tumblers from the slots 3 and 55 4, these tumblers are brought into line with unslotted portions of the shell 2 so that the key may not then be withdrawn. In order to withdraw the key, it is necessary to reverse the movement of the key to bring the tumblers into register with the slots 3 and 4. When the key is withdrawn, the ends of the 60 tumblers are receivable in the slots 3 and 4. 65

The wards upon the key may be so related to the tumblers that some of the tumblers may be positively moved into the slots by the action of the key.

Hitherto, gravity or inertia has been relied upon to project the tumblers or certain of the tumblers into the slots of the guard or shell receiving the same and to maintain the ends of the tumblers in said slots, the key being absent. In accordance with my invention, I provide springs 24, 25 which are carried by and moved bodily with the tumblers 70 20, 21 and which serve to project those tumblers into the slots 3 and 4 that are not projected into the slots by the action of the key and to maintain all of the tumblers however projected into said slots in their projected positions. In the preferred embodiment of the invention, the tumblers are formed of strip spring metal and the springs 80 24, 25 are integrally formed therewith, these springs being in the nature of tongues which project into the bore enlargement 18' of the tumbler barrel when the tumblers project into the slots 3 and 4 in the lock shell or 90 guard 2. The bore enlargement 18' is margined by cam-shaped corners 26 on the body of the tumbler barrel which engage the bases of the tongues when the tumblers are in locking position and upon which corners the 95 tongues ride when the tumblers are operated by the key to withdraw them from said slots. In this withdrawing movement of the tumblers, the tongues ride upon the cam-shaped portions 26 and are placed under tension, as illustrated in Fig. 11, the tongues remaining under tension during the presence of the key within the tumbler barrel and yielding their tension when the key is removed so as to project those tumblers into 100 the slots 3 and 4 which are not actually thus projected by the key and holding all tumblers in their projected positions following the withdrawal of the key. The spring 105 tongues 24 and 25 upon the two sets of tumblers 20 and 21 desirably cross when the key is withdrawn and the tumblers are in locking position so as to make it difficult to pick the lock. The tumbler barrel is formed with grooves 27 which receive the ends of the 110 tongues in the event that the tumblers are moved beyond the normal range of their key effected movement in an attempt to pick the lock, the tumblers thereupon being held in locking position and the lock being rendered 115 inoperative. It is to be observed that the slots in the key receiving member 12 which receive the tumblers also receive the base or connecting ends of the tongues upon the tumblers, the unattached ends of these 120 tongues being outwardly deflected to have holding engagement with said key receiving member to maintain the tumblers in position when placed in engagement with the guard. 125 130

Changes may be made without departing from the invention.

Having thus described my invention, I claim:

5. 1. A lock including a guard; two tumblers each formed of strip metal and movable into one position into engagement with the guard and into an alternative position out of such engagement and operable by a key into one of its positions; and a key receiving member, each of said tumblers having a spring tongue which engages said member and is pressed thereupon and toward the body of the tumbler when the tumbler is moved into one position by the key and serves to hold the tumbler in its other position upon removal of the key, said springs extending toward each other and crossing when each tumbler is in one of its alternative positions.
10. 2. A lock including a guard; two tumblers each formed of strip metal and movable into one position into engagement with the guard and into an alternative position out of such engagement and operable by a key into one of its positions; and a key receiving member, each of said tumblers having a spring tongue which engages said member and is pressed thereupon and toward the body of the tumbler when the tumbler is moved into one position by the key and serves to hold the tumbler in its other position upon removal of the key, said spring tongues extending toward each other.
15. 3. A lock including a guard; a key operated tumbler formed of strip metal and movable into one position into engagement with the guard and into an alternative position out of such engagement; and a key receiving member carrying said tumbler and formed with a slot in which the tumbler is movable into its alternative positions, said tumbler having a spring tongue whose base is also received in said slot and whose unattached end is outwardly deflected to have holding engagement with said key receiving member.
20. 4. A lock including a guard; a key operated tumbler formed of strip metal and movable into one position into engagement with the guard and into an alternative position out of such engagement; and a key receiving member carrying said tumbler and formed with a slot in which the tumbler is movable into its alternative positions, said tumbler having a spring tongue whose base is also received in said slot and whose unattached end is outwardly deflected to have holding engagement with said key receiving member.
25. 5. A lock including a guard; a key operated tumbler formed of strip metal and movable into one position into engagement with the guard and into an alternative position out of such engagement; and a key receiving member carrying said tumbler and formed with a slot in which the tumbler is movable into its alternative positions, said tumbler having a spring tongue whose base is also received in said slot, said key receiving member being formed with a groove positioned and serving to receive the unattached end of the tongue when the tumbler is moved beyond the normal range of its key effected movement, the unattached end of the tongue being disposed to be normally clear of said groove.
30. 6. A lock including a guard; a key operated tumbler formed of strip metal and movable into one position into engagement with the guard and into an alternative position out of such engagement; and a key receiving member carrying said tumbler and formed with a slot in which the tumbler is movable into its alternative positions, said tumbler having a spring tongue whose base is also received in said slot, said key receiving member being formed with a groove positioned and serving to receive the unattached end of the tongue when the tumbler is moved beyond the normal range of its key effected movement, the unattached end of the tongue being disposed to be normally clear of said groove.
35. 7. A lock including a guard; a key operated tumbler formed of strip metal and movable into one position into engagement with the guard and into an alternative position out of such engagement; and a key receiving member carrying said tumbler and formed with a slot in which the tumbler is movable into its alternative positions, said tumbler having a spring tongue whose base is also received in said slot and whose unattached end is outwardly deflected to have holding engagement with said key receiving member.
40. 8. A lock including a guard; a key operated tumbler formed of strip metal and movable into one position into engagement with the guard and into an alternative position out of such engagement; and a key receiving member carrying said tumbler and formed with a slot in which the tumbler is movable into its alternative positions, said tumbler having a spring tongue whose base is also received in said slot and whose unattached end is outwardly deflected to have holding engagement with said key receiving member.
45. 9. A lock including a guard; a key operated tumbler formed of strip metal and movable into one position into engagement with the guard and into an alternative position out of such engagement; and a key receiving member carrying said tumbler and formed with a slot in which the tumbler is movable into its alternative positions, said tumbler having a spring tongue whose base is also received in said slot and whose unattached end is outwardly deflected to have holding engagement with said key receiving member.
50. 10. A lock including a guard; a key operated tumbler formed of strip metal and movable into one position into engagement with the guard and into an alternative position out of such engagement; and a key receiving member carrying said tumbler and formed with a slot in which the tumbler is movable into its alternative positions, said tumbler having a spring tongue whose base is also received in said slot and whose unattached end is outwardly deflected to have holding engagement with said key receiving member.

formed with a slot in which the tumbler is movable into its alternative positions, said tumbler having a spring tongue whose base is also received in said slot and whose unattached end is outwardly deflected to have holding engagement with said key receiving member, said key receiving member being formed with a groove positioned and serving to receive the unattached end of the tongue when the tumbler is moved beyond the normal range of its key effected movement, the unattached end of the tongue being disposed to be normally clear of said groove.

5. A lock including a guard; a key operated tumbler formed of strip metal and movable into one position into engagement with the guard and into an alternative position out of such engagement; and a key receiving member carrying said tumbler and formed with a slot in which the tumbler is movable into its alternative positions, said tumbler having a spring tongue whose base is also received in said slot, said key receiving member being formed with a groove positioned and serving to receive the unattached end of the tongue when the tumbler is moved beyond the normal range of its key effected movement, the unattached end of the tongue being disposed to be normally clear of said groove.

6. A lock including a guard; a key operated tumbler formed of strip metal and movable into one position into engagement with the guard and into an alternative position out of such engagement; and a key receiving member carrying said tumbler and formed with a slot in which the tumbler is movable into its alternative positions, said tumbler having a spring tongue whose base is also received in said slot, said key receiving member being formed with a groove positioned and serving to receive the unattached end of the tongue when the tumbler is moved beyond the normal range of its key effected movement, the unattached end of the tongue being disposed to be normally clear of said groove.

In witness whereof, I hereunto subscribe my name.

HARRY A. DOUGLAS.
